UNITED STATES PATENT OFFICE.

JOHN R. MITCHELL, OF MONTCLAIR, NEW JERSEY.

THREAD-GUIDE.

1,087,502.

Specification of Letters Patent.

Patented Feb. 17, 1914.

Application filed May 28, 1913. Serial No. 770,455.

To all whom it may concern:

Be it known that I, JOHN R. MITCHELL, a citizen of the United States, and resident of Montclair, Essex county, State of New Jersey, have invented certain new and useful Improvements in Thread-Guides, of which the following is a specification.

Thread used in modern textile machinery is subjected to a variety of vibrations that tend to dislodge the thread from the eye of the thread guide or hook and this results in numerous annoyances.

It is the principal object of the present invention to construct a guide for thread, yarn and the like which will be much more effective in its function of retaining thread and of properly guiding the same during all conditions of service.

The above and other objects and the novel features of the invention will be apparent from the following description, taken in connection with the drawing, in which—

Figure 1 is a side elevation, partly in section, showing one form of the improved thread guide, and Fig. 2 is a side elevation, partly in section, showing another guide embodying the invention.

Referring to the drawing, each guide comprises a stem A and a body B formed integral with the stem, the guide being made of any suitable material such as glazed porcelain, enameled metal or the like. Each guide is provided with a socket S which enters the stem at its lower face and extends part way into the stem and is adapted to receive the end of a drop wire or other suitable support.

The eye which receives the thread and guides the same comprises an irregular opening extending transversely through the body B and has an aperture or enlarged part 5 at its lower end into which the thread first passes as it enters the eye through the inclined, restricted inlet passageway 6 which opens into the enlarged portion 5 intermediate the ends of the latter.

The upper wall 7 of the passageway 6 is longer than the lower wall 8 and overhangs the latter at both ends, the downward projecting end 9 on the exterior of the guide serving as a hook and forming a continuation of the passageway 6 with the outer adjacent wall of the guide so as to assist in threading the guide. The overhanging edge

10 prevents the loose thread from accidentally passing out through the passageway 6, dropping it into the lower part of the enlargement 5 when it drops downwardly out of the curved passageway 11. 60

The curved passageway 11 opens into the aperture or enlarged part 5 and extends substantially vertically of the body portion B and opens at its upper end into the side of a second elongated enlarged part or transverse aperture 13 which has the two thread guiding parts 14 and 15 at its opposite ends, the guiding part 14 being in about the same relation to the passageway 11 that the lower end of the guiding part 5 is to the passageway 6. The two apertures 5 and 13 are thus connected by a comparatively long and narrow curved channel 11. The upper guiding part 15 is disposed substantially above the vertical passageway 11 and is separated therefrom by the lip 16 which overhangs the edge 17 at the inlet of the passageway 11 into the enlargement 13. The lip serves to divide the long aperture 13 into two thread retaining portions 14 and 15 which provide supporting ledges for the thread or yarn. The thread, when it is threaded into the guide and tensioned, will pass into the thread retaining portion 15 and contact with the upper wall 18 thereof 85 and when slightly slack and vibrating will be prevented from dropping into the passageway 11, on account of the overhanging lip 16 which tends to retain the thread in the portion 15 of the eye or guides the slack thread into the portion 14 of the enlargement 13. On subsequent tensioning of the thread it will pass through the narrow passage 19 into the part 15 and again bear against the top wall 18 of the latter. A 90 slight depression 20 in the lower wall of the portion 15 adjacent the lip 16 will catch and form a hook with the lip 16 to prevent the thread from dropping out of the portion 15 under ordinary conditions. 100

The upper portion 15 of the eye shown in Fig. 2 has an angular part 21 which, with the lip 23 that overhangs the lip 16, also serves as a hook to prevent the accidental passage of the thread through the passage 19. 105

The provision of the curved passageway 11 connecting the apertures or enlargements 5 and 13 and the thread retaining part 15 with the lip 16 which co-operates 110

therewith provides a more effective and reliable hook for drop lines in use on modern textile machinery, and has the advantage over thread guides now in use that it retains the thread under normal conditions in the portion 15 and rarely, under ordinary conditions of service, does the thread escape from the enlargement 13 and through the passage 11.

10 What I claim is:

1. A thread guide comprising a body portion having an eye consisting of two transverse apertures extending through the body joined by a narrow passageway one of said apertures having a lip or projection extending into the same to divide it into two thread retaining portions.
2. A thread guide comprising a body portion provided with an eye consisting of two transverse apertures in the ends of the body portion connected by a passageway opening into one of said apertures intermediate the ends of the latter, said last named aperture having thread supporting portions at opposite sides of the entrance of said passageway.
3. A thread guide comprising a body portion having an eye consisting of two apertures extending through the body portion and joined by a passageway extending longitudinally of the guide and opening into the upper aperture intermediate its ends, a lip dividing the upper aperture into two

thread retaining portions, and an inlet slot opening into the lower aperture.

4. A thread guide having a body portion provided with an eye including a passageway extending substantially longitudinally of the body portion and opening into an elongated aperture intermediate the ends of the aperture, and a lip extending into the aperture and forming two thread guiding portions of said aperture.

5. A thread guide consisting of a body portion formed integrally with a stem which has a socket therein, an eye in the body portion comprising a relatively narrow curved passageway extending longitudinally of the body portion and connecting two apertures extending transversely through the body portion, one of said apertures being elongated, the longitudinal passageway opening into said elongated aperture intermediate the ends thereof, a lip formed adjacent the point where the longitudinal passageway opens into the elongated aperture, said lip dividing the elongated aperture into two thread retaining portions, and an inlet slot opening into the other aperture.

In testimony whereof I affix my signature in presence of two witnesses.

JOHN R. MITCHELL.
